UNITED STATES PATENT OFFICE.

CYRUS E. MOREHOUSE, OF MILWAUKEE, WISCONSIN.

BINDER.

1,250,204.

Specification of Letters Patent. Patented Dec. 18, 1917.

Application filed March 2, 1917. Serial No. 151,999.

To all whom it may concern:

Be it known that I, CYRUS E. MOREHOUSE, a citizen of the United States, residing at Milwaukee, in the county of Milwaukee, 5 State of Wisconsin, have invented certain new and useful Improvements in Binders, of which the following is a specification.

This invention relates to improvements in binders.

10 My improvements are particularly designed by me for the binding of sheets perforated at their binding edges for the reception of posts, the binders being well adapted for the permanent binding of sheets transferred from temporary binders although, of course, the binders are as well adapted as the original binders for the sheets.

The main objects of this invention are:

First, to provide an improved binder 20 which is very simple and economical in its parts and one in which the parts are quickly assembled and adjusted to the sheets to bind the same.

Second, to provide a binder having these 25 advantages which is very secure.

Further objects, and objects relating to structural details, will definitely appear from the detailed description to follow.

I accomplish the objects of my invention 30 by the devices and means described in the following specification. The invention is clearly defined and pointed out in the claims.

A structure which is a preferred embodiment of my invention is clearly illustrated 35 in the accompanying drawing forming a part of this specification, in which:

Figure I is a detail longitudinal section through one of the binding posts of a binder 40 embodying my invention on a line corresponding to line 1—1 of Fig. II.

Fig. II is a detail horizontal section on a line corresponding to line 2—2 of Fig. I, the covers being omitted.

45 Fig. III is a similar detail section of a modified form of my invention, the modification being in the form of the post opening in the binding bar.

Fig. IV is a side view of one of the binding posts.

Fig. V is a detail vertical section of another embodiment of my invention.

Fig. VI is a detail vertical section showing still another modification, the modifica-

tion being in the form of a post expanding 55 member.

Fig. VII is a detail vertical section of an embodiment of my invention in which the binding post is secured to both binding bars by expanding the ends of the post. A modified form of the binding bars is also shown.

Fig. VIII is a detail vertical section of another embodiment of my invention in which post expanding members are provided on both binding bars.

Fig. IX is a side view of the post employed in the embodiment shown in Figs. 65 VII and VIII.

Fig. X is a plan view of the blank from which the post shown in Fig. IX is formed.

Fig. XI is a detail longitudinal section, similar to that of Fig. I, of a structure adapted for slotted sheets, posts being U-shaped in cross section. Both ends of the posts are extended into the binding bars as 75 in the embodiment shown in Fig. VIII.

Fig. XII is a detail section on a line corresponding to line 12—12 of Fig. XI.

Fig. XIII is an enlarged detail section on a line corresponding to line 13—13 of 80 Figs. XI and XII.

Fig. XIV is a plan view of the blank from which the posts shown in Figs. XI, 85 XII and XIII is formed.

Fig. XV is a detail longitudinal section corresponding to that of Fig. XI of another modification in which the U-shaped posts are adapted for sheets having round holes therein, the round expanding members being also used.

Fig. XVI is a detail section on a line 90 corresponding to line 16—16 of Fig. XV.

Fig. XVII is a detail view on a line corresponding to line 17—17 of Fig. XV.

In the drawing, similar reference characters refer to similar parts throughout the several views, and the sectional views are taken looking in the direction of the little arrows at the ends of the section lines.

Referring to the drawing, I provide a 100 pair of binding members or bars 1 and 2 and binding posts 3 coacting therewith. The binding bars are preferably formed of strips of metal folded longitudinally to provide spaced bar members. In the embodiment shown in Figs. I and II the inner member of the bar 2 is slotted at 4 to receive the post 3 which is provided with a 105

flange 5 at one end, the flange being clamped between the bar members after its engagement with the slot. This provides a convenient means for assembling and supporting the post on one binding bar.

The perforation or hole 6 of the binding bar 1 is disposed opposite to the slot 4 and is adapted to receive the other end of the post 3 and also an expanding member 7. 10 This expanding member has a beveled head preferably of such diameter as to retain it in place with its head between the binding bar members, as illustrated. When the post is forced longitudinally into the perforation 6 it engages the expanding member and is expanded, as at 9, within the space between the binding bar members thereby securing the post to the binding bar members, as illustrated. When the post is forced longitudinally into the perforation 6 it engages the expanding member and is expanded, as at 9, within the space between the binding bar members, thereby securing the post to the binding bar 1.

25 The expanding member may be conveniently formed of a rivet. I have shown the end of the expanding member as tapered in certain embodiments, although it may be left in its commercial form, as shown in Fig. VI.

30 The sheets 8 are perforated to receive the posts.

35 My improved binder is well adapted for holding sheets which have been previously bound in loose leaf binders of the post type, although, of course, it may be used equally as well as the original binder for the sheets.

40 The covers 10 and 11 are provided with suitable coverings or facings 12 and 14 which are extended upon the binding bars and constitute the hinge connections 13 for the covers. These coverings may be extended at the rear of the binding bars and form a back 13' for the binder.

45 In the embodiment shown in Fig. III a hole 15 is provided instead of the slot 4. The slot is of advantage over the hole, however, in that it permits the folding of the binding bar before the post is introduced. 50 In the embodiment shown in Fig. III it is necessary to insert the post prior to the folding of the binding bar.

55 In the embodiment shown in Fig. V both edges of the binding bar are folded over at 16 and 17 to clamp the flange of the post. The expanding member 18 on the bar 1 is formed by striking up a portion of the body of the bar.

60 In the embodiment shown in Fig. VI the expanding member 19 is in the form of a commercial rivet.

65 In the embodiment shown in Figs. VII and VIII the post is secured to both binding bars by expanding its ends into the perforation or holes provided therefor. In the

embodiment of Fig. VII an annular expanding member 20 is disposed to embrace the expanded end 21 of the post and serve as expanding means when the post is forced longitudinally into the slot. In the embodiment of Fig. VIII both binding bars are equipped with the rivet-like form of expanding member shown in Fig. I.

70 The post 22 is preferably formed from a sheet metal blank 23. To facilitate the expanding the posts are preferably notched at 24.

75 In the embodiment of Fig. VII the bars 25 and 25' are formed of inner and outer bar members secured together by the rivets 26, washers 27 being interposed between the members to properly space them.

80 In Figs. XI to XVII the posts 28 are U-shaped in cross section, that is, the blanks 29 from which they are formed are not formed of a complete tube but are formed of a U-shape, as shown in Fig. XII. These U-shaped posts are well adapted for the sheets 30 having slots 31 in their binding edges. The expanding members 32 of this modification are elongated but shaped somewhat like a horseshoe nail head. The posts are formed so that their bight or inner edges are of greater diameter than their outer edges, so that when they are disposed in the slots of the sheets and expanded the sheets are securely bound. This form is desirable in that it may be conveniently employed as it is somewhat more convenient to saw the slots of a quantity of sheets than to punch 90 holes therein.

95 In the modification shown in Figs. XV, XVI, XVII, the post holes are punched in the sheets but the posts have the same form as in Figs. XI to XIII. The expanding 100 members 7, the same as shown in Figs. I, VII, and VIII are here employed.

105 With the parts thus arranged, I provide a binder which can be quickly assembled to bind the sheets and one in which the 110 sheets are permanently held or bound. It is found that there are various instances where it is desirable to permanently bind sheets such as have been previously held in loose sheet binders, thereby providing 115 permanent records, or for storage purposes, and my improved binder is highly satisfactory for this purpose and in addition may be furnished so economically that it is particularly well adapted as a storage 120 binder as well as for current use.

125 In the embodiment shown in Fig. VIII posts may be furnished to the users of different lengths so that the binder may be adapted to the body of sheets it is desired to bind.

130 I have illustrated and described several embodiments of my invention but have not attempted to illustrate certain other embodiments or adaptations which I contem-

plate as I believe the disclosure made will enable those skilled in the art to embody or adapt the same as conditions may require. I have illustrated only a single post but it will be readily understood that the binders may be provided with as many posts as desired.

Having thus described my invention, what I claim as new and desire to secure by Letters Patent, is:

1. In a binder, the combination of a pair of binding bars formed of strips folded longitudinally providing spaced bar members, the inner member of one bar having a transverse slot therein extending from its edge and the inner member of the other bar having a perforation opposite said slot, an expanding member provided with a beveled head disposed in said perforation with its head between the bar members, the diameter of the head exceeding that of the perforation whereby the expanding member is retained, and a tubular binding post longitudinally slotted at one end and having a flange at the other end disposed in said slot with its flange between the bar members and with its other end disposed in said perforation in engagement with said expanding member and expanded upon the head thereof between the bar members.
2. In a binder, the combination of a pair of binding bars formed of strips folded longitudinally providing spaced bar members, the inner member of one bar having a transverse slot therein extending from its edge and the inner member of the other bar having a perforation with its head between the bar members, and a tubular binding post having a flange at the other end disposed in said slot with its flange between the bar members and with its other end disposed in said perforation in engagement with said expanding member and expanded upon the head thereof between the bar members.
3. In a binder, the combination of a pair of binding bars comprising spaced bar members, the inner member of one bar having a transverse slot therein extending from its edge and the inner member of the other bar having a perforation opposite said slot, a tubular binding post having a flange at one end disposed in said slot with its flange between the bar members, its other end being adapted to be engaged in said perforation, and an expanding member provided with a beveled head disposed in said perforation with its head between the bar members for engaging said post and expanding the end thereof between the bar members.

4. In a binder, the combination of a pair of binding bars comprising spaced bar members, the inner member of one bar having a transverse slot therein extending from its edge and the inner member of the other bar having a perforation opposite said slot, a

tubular binding post having a flange at one end disposed in said slot with its flange between the bar members, its other end being adapted to be engaged in said perforation, and an expanding member for engaging said post and expanding the end thereof between the bar members.

5. In a binder, the combination of a binding bar formed of a folded piece providing spaced bar members, the inner member having a perforation therein adapted to receive a post, an expanding member provided with a beveled head disposed in said perforation with its head between the bar members, the diameter of the head exceeding that of the perforation whereby the expanding member is retained, and a tubular binding post disposed in said perforation in engagement with said expanding member and expanded upon the head thereof between the bar members.

6. In a binder, the combination of a binding bar formed of a folded piece providing spaced bar members, the inner member having a perforation therein adapted to receive a post, an expanding member disposed in said perforation, and a tubular binding post disposed in said perforation in engagement with said expanding member and expanded thereon between the bar members.

7. In a binder, the combination of a binding bar comprising spaced members, the inner bar member having a perforation therein, an expanding member provided with a beveled head disposed in said perforation with its head between the bar members, the diameter of the head exceeding that of the perforations in the bar member wherein it is retained, and a tubular post inserted in said perforation and expanded between the bar members by said expanding member.

8. In a binder, the combination of a tubular post, a binding bar comprising spaced members, the inner bar member having a perforation therein for receiving said tubular post, and an expanding member disposed in said perforation for expanding said tubular post between said members.

9. In a binder, the combination of a binding member having a tubular post thereon, a coacting binding member formed of a strip folded longitudinally providing spaced bar members the inner of which has a perforation adapted to receive said post, and an expanding member provided with a head disposed in said perforation with its head between the bar members, said post being disposed in said perforation and expanded upon the expanding member between the bar members.

10. In a binder, the combination of a binding bar, a tubular post mounted on said bar, a second binding bar comprising a pair of spaced bar members, the inner member

having a perforation for receiving said post, and means carried by said second binding bar for expanding the end of the post between the bar members.

5. 11. In a binder, the combination of a pair of binding bars formed of strips folded longitudinally providing spaced bar members, the inner bar members having post openings therein, and a post arranged through said openings and having end enlargements disposed between said bar members and exceeding the diameter thereof whereby the post is retained, one of said binding members being provided with means 15 for holding, for the purpose specified.
12. In a binder, the combination of a pair of binding bars formed of strips each folded longitudinally providing spaced bar members, the inner bar members having post openings therein, and a post arranged through said openings and having end enlargements disposed between said bar members and exceeding the diameter thereof whereby the post is retained.
20. 13. In a binder, the combination of a binding bar provided with a recess and with

a post opening from the inner side of the recess, a post adapted to be engaged in said opening, and means retained normally within the chamber for expanding and holding the end of the post expanded into said chamber when the post is introduced longitudinally thereto.

30. 14. In a binder, the combination of a binding bar provided with a post opening, a tubular post, and an expanding member assembled upon said binding bar independently of said post for expanding the same therein.

35. 15. In a binder, the combination of a binding bar provided with a post opening, a post having an expansible end, and an expanding member assembled upon said bar independently of said post for expanding the same therein.

40. In witness whereof, I have hereunto set my hand and seal in the presence of two witnesses.

CYRUS E. MOREHOUSE. [L. S.]
